UNITED STATES PATENT OFFICE.

FRANCIS L. FISHER, OF SAN FRANCISCO, CALIFORNIA, ASSIGNOR TO WILLIAM C. MYSELL, OF SAN FRANCISCO, CALIFORNIA.

ELECTION-BOOTH.

1,120,298.

Specification of Letters Patent.

Patented Dec. 8, 1914.

Application filed April 27, 1914. Serial No. 834,764.

To all whom it may concern:

Be it known that I, FRANCIS L. FISHER, a citizen of the United States, residing at San Francisco, in the county of San Francisco, 5 State of California, have invented a new and useful Election-Booth, of which the following is a specification in such full and clear terms as will enable those skilled in the art to construct and use the same.

10 This invention relates to a voting booth and its object is to produce a voting booth which will have its parts all secured together so that the booth may be set up and a curtain thrown thereover with the minimum 15 labor.

Another object of the invention is to produce a voting booth which will not require any screws or other fixtures to hold the same upright.

20 A further object of the invention is to provide a voting booth with means whereby the person using the same will involuntarily place his feet upon a portion of the booth thereby preventing it from being 25 easily upset.

Another object of the invention is to produce a support for the shelf, which support also acts as means for securing the shelf in its folded-up position when the booth is 30 ready to be shipped.

Another object of the invention is to provide a curtain which will have its corners so shaped as to lend additional security to the booth when set up, the curtain acting as 35 a brace for the upper portion of the booth.

Other objects of the invention will appear as the description proceeds.

An embodiment of the invention is shown in the drawing in which the same reference 40 numeral is applied to the same portion throughout, but I am aware that there are many modifications thereof,

Figure 1 is a side elevation of the complete booth, Fig. 2 is a side elevation of a 45 portion of two uprights showing the manner of securing the uprights together and showing the manner of securing the shelf in position ready for shipment, Fig. 2^A is a front elevation of the lock used for securing 50 the upper portion of the booth to the lower portion when the booth is set up, Fig. 3 is a view illustrating the booth partially raised, Fig. 4 is a perspective view of the complete booth showing the curtain thereon, one portion 55 of the curtain being thrown back, and

Fig. 5 is a view of the booth when folded in position ready for shipment.

The numeral 1 indicates one of the side members of the base of the booth, 2 representing a similar member connected with 60 the first piece by means of the cross bar 3, said cross bar being so placed that when the person using the booth is in a position to mark his ballot that he will naturally stand on the cross bar 3, thus steadyng the booth 65 and preventing it from being easily upset.

Connected with the bars 1 and 2 by means of the hinges 4 and 5 are the uprights 7 and 8, said uprights being connected with each other by means of cross pieces 6 and 14, the 70 parts 1 and 7 and 2 and 8 are connected respectively by means of the pivoted braces 9 and 10 and 11 and 12, said braces being pivoted to each other and to the side and base pieces respectively in a well known manner, 75 small lugs 10' and 12' holding said braces when they are extended, as illustrated in Figs. 1, 3 and 4.

The uprights 7 and 8 are connected with uprights 23 and 13 respectively by means of 80 hinges 32, one for each upright 7 and 8 and the two sets of uprights are held in line as indicated in Figs. 1 and 2 by means of a pair of plates 35, each of said plates having an opening 36 for a screw 37 and a slot 38 to 85 be placed over a screw 39. When the booth is folded up the plate 35 is rotated 180 degrees from the position shown in Figs. 1 and 2 so that it will lie on the upright 28 out of the way.

The uprights or corner posts 23 and 13 are connected by means of the cross pieces 14', 15 and 16. The cross piece 14' carries two blocks 28', which blocks carry hinges 31 for the support of one edge of the shelf 28, 95 two chains 26 supporting the other edge of the shelf when it is in the horizontal position indicated in Figs. 1 and 4. When it is desired to fold the shelf up ready for packing the chains 26 are put around the cross piece 15 and a cotter pin 30 is inserted in a hole 29 in each corner post. The chains thus serve to support the shelf in position for use as well as to hold the shelf in a fixed 100 position when the booth is to be shipped.

Each of the corner posts 13 and 23 carries a hinge at its upper end, see 22 and 22', which hinges are connected respectively with forwardly extending pieces 19 and 19', and the frame formed by the pieces 17, 18, 110

19 and 19' is supported by means of the pivoted braces 20 and 21 and 24 and 25 respectively, the same as the braces used on the lower part of the booth.

5 When the booth is set up the curtain C is thrown thereover, said curtain having a top portion T to which the depending sides of the curtain are connected, so that when the curtain is placed over the top of 10 the frame it braces that frame and prevents it from being moved diagonally.

When the booth is to be shipped it is folded up in the position shown in Fig. 5, the curtain being rolled up and secured therefor 15 for convenience. When the booth is to be set up it is placed upon the floor as shown in Fig. 5, whereupon the top and side frames are raised to the position shown in Fig. 3. The braces are then placed in 20 the position shown in Fig. 3 whereupon the two upper frames are folded up to the position shown in Fig. 1. The curtain is placed over the top frame and the booth is ready for use, and since the board 3 is in a location 25 where a person will naturally stand with the feet thereon when attempting to write on the shelf, there is no danger of upsetting the booth when in use.

Having thus described my invention what 30 I claim as new and desire to secure by Letters Patent of the United States, is as follows, modifications within the scope of the claims being expressly reserved:

- 35 1. An election booth comprising a base frame, a top frame and two side frames hingedly connected to each other and to the top and base frames respectively, and forming a single side for the election booth when all of the frames are extended.
- 40 2. In an election booth, a base frame and a top frame, two frames hingedly connected with the base frame and top frame and with each other and forming a single side when all of the frames are extended, and 45 braces connected with the side frames and

the top and bottom frames for holding the several frames extended.

3. In an election booth, a base frame and a top frame, two other frames hingedly connected with the base frame and top frame 50 respectively and with each other, braces connecting the top frame and bottom frame with the side frames, and a shelf hingedly connected to the lower edge of the upper side frame. 55

4. In an election booth, a base frame having a foot board extending transversely thereof, a top frame, two side frames hingedly connected with each other and with the top and base frames, and a shelf 60 hinged to one of the side frames.

5. An election booth comprising four hingedly connected frames forming respectively base, sides and top of the booth, braces connected with the base, top and sides of 65 the booth, a shelf hingedly connected with one of the side frames, a chain for supporting the outer edge of said shelf when in use, and a pin carried by said chain and adapted to be inserted in a hole in one of the side 70 frames for securing the shelf in its folded-up position.

6. An election booth comprising a base frame having a transversely extending foot board, a side frame hinged to the base 75 frame, braces connecting the side frame and base frame, a second side frame hinged to the first side frame and forming therewith when extended a single side, a top hinged to the second side frame, and braces for 80 supporting the top when in an extended position.

In testimony whereof I have hereunto set my hand this 22d day of April A. D. 1914, in the presence of the two subscribed witnesses. 85

FRANCIS L. FISHER.
